UNITED STATES PATENT OFFICE.

FREDERICK C. HERBERMANN, OF MOUNT VERNON, NEW YORK.

SELF-WINDING CLOCK.

Application filed May 22, 1926, Serial No. 110,896. Renewed December 28, 1927.

This invention relates to clocks provided with magnetically operated winding mechanism particularly adapted for use in and with the installations of automobiles.

5 The principal object of the invention is to provide such a clock with a winding mechanism simple in construction, certain in operation and of minimum cost of manufacture, the said winding mechanism being operable 10 automatically and intermittently by magnetically operated means, the magnets being intermittently energized from the battery installed in the automobile.

15 The invention, therefore, consists in a clock mechanism combined with a magnetically operated winding mechanism, the magnets being intermittently energized and de-energized by electric contacts made and broken during and by virtue of the normal operation 20 of the clock, the contacts and the magnets being in circuit with the battery installed in the automobile.

25 The invention further consists in the construction and arrangement of the various elements of the device as will be hereinafter more particularly pointed out and explained.

Referring to the drawings:

30 Fig. 1 is a longitudinal sectional view, with parts in elevation, showing the interior structure of the clock and the winding mechanism therefor.

35 Fig. 2 is an end elevation with the cover removed showing the poles of the magnets, the armature and the make and break mechanism, the armature being illustrated in one of its extreme positions of movement at the moment of closing the circuit of the magnet coils.

40 Fig. 3 is a view similar to Fig. 2 showing the position of the electrical contacts at the moment of or immediately after the breaking of the circuit of the magnet coils, the trap having sprung closed.

45 Fig. 4 is a fragmentary view in detail showing the position of the contacts of the armature just after the breaking point of the circuit, the trap shown open.

50 Fig. 5 is a horizontal section on line 5—5 of Fig. 1, the connecting base plates of the magnets being shown in dot and dash lines.

Fig. 6 is an enlarged section taken on line 6—6 of Fig. 1.

Fig. 7 is a section on line 7—7 of Fig. 6.

Fig. 8 is a sectional view, with parts in elevation, of the contact plate and connecting parts on line 8—8 of Fig. 2.

Fig. 9 is a detail partly in section, taken on line 9—9 of Fig. 2.

Fig. 10 is a perspective view of the make and break contact lever.

Fig. 11 is a perspective view of the element hereinafter referred to as the trap by means of which the movement of the make and break contact lever is governed.

In the drawings, in which like reference characters refer to like parts in the several views, the clock mechanism is of the usual construction, some of the elements of which in the interest of clearness are omitted from the drawing and will not be specifically herein- 70 after referred to in view of the fact that clock mechanisms as such are old and of the further fact that the present invention may be applied to the ordinary clock or watch movement, the structure of which is well known to 75 those skilled in the art.

The clock mechanism with its attached magnetically controlled winding mechanism is mounted in a casing 10 which may be suitably fitted and secured to any suitable support and particularly the ordinary instrument board of an automobile.

The face plate 12, bearing the minute and hour indications of the clock is rigidly secured to the casing at its open end by means 85 of the usual ring 14, which is preferably screwthreaded at 16 and which supports the crystal 17 in the usual way.

I also mount inside of the casing a skeleton supporting structure for the clock mechanism as a unit, the shafts, the magnets and the armature, this skeleton supporting structure consisting broadly of parallel plates 20, 22, 24 and 26, the plates being connected together in parallel position by a series of eight 95 connecting rods or posts, six of which are shown in Fig. 1 as 28, 30, 32, 34, 36 and 38, the other two being omitted from Fig. 1 in the interest of clearness, the end of one however being shown at 40 in Figs. 2 and 3.

The mechanical elements of the clock essential to a clear understanding of my invention and a portion of the winding mechanism thereof will now be described.

Extending centrally through the skeleton 105 supporting structure is a shaft 50, sections of

which vary in diameter for reasons which will hereinafter clearly appear. A thumb wheel or handle 52 is secured to one of the free ends of the shaft by means preferably of 5 a screw or bolt 54 having a screwthreaded inner end engaging a correspondingly threaded hole in shaft 50, the head of said screw engaging the outer face of the thumb wheel 52, preferably milled for the purpose of providing a ready means for turning the shaft 10 and setting the hands when desired, the thumb wheel, of course, extending outside of the casing 10 in a position to be grasped by the operator. The shaft is journaled at 56 in 15 the plate 20, and extends outwardly in reduced cross section at 58. On this portion 58 of the shaft 50 is mounted a sleeve 60 provided at one end with a gear 62, and upon the other end of which is mounted the minute hand M secured by a washer w in the usual way. The hour hand H is in turn mounted upon the outer projecting end of a sleeve 64 journaled in the face plate 12, and upon the other or inner end of which sleeve 20 25 is a gear 66. The gears 66 and 62 are intermeshed with other gears, a portion of which is shown at 68 in the well known way so that the minute hand will make twelve revolutions of the clock dial while the hour hand revolves 30 but one, all of which is well known to those skilled in the art and does not require further description in order to have a full understanding of the construction and principles of my invention.

35 Upon the shaft 50 is mounted and fitted a sleeve 70, which passes through and is journaled in the parallel plates 24 and 26. Upon one end of this sleeve is mounted the limb of a four armed armature A and it is fixedly 40 secured thereto by means of a set screw 72. At the other end of the sleeve 70 is secured at 74 one of the free ends of the main spring S, the other free end of the main spring being secured to a stud 76 projecting from the adjacent face of the plate 24 at a point near 45 the circumference thereof, as clearly shown in Fig. 1. I also secure to the end of the sleeve 70 by a pin 78, or by any suitable means, a disc 80, having inclined ratchet teeth 82 50 cut in its periphery. A collar 86 is fixedly mounted upon the section 51 of the main shaft 50, by means of a set screw 84. Two sliding collars 88 and 90 are also mounted upon the section 51 of the shaft 50, the collar 88 55 having the disc 92 rigidly mounted thereon by brazing or in any suitable manner. A pawl 94 is pivoted at 96 near the periphery of the disc 92, the point of the pawl engaging the teeth 82 on the periphery of the disc 60 80, as clearly indicated in the drawings.

Rigidly secured to the sleeve 88 is the governing or master gear wheel 98 which meshes with the other gearing of the clock mechanism which latter is not necessary to here describe for it has no relation otherwise to the

present invention. Consequently, in the interest of clearness, the remaining gearing or other operating elements such as the escapement, &c., of the clock mechanism are neither illustrated nor will they be further referred to herein as such constructions are well known to those skilled in the art.

The coil spring 91 surrounds the sleeve 90 and engages at opposite ends the fixed collar 86 and the flange of the slidable collar 90 75 in order to hold the slidable collar 88 and connecting plate 92 in place.

From the above description it is readily seen that the minute and hour hands of the clock may be adjusted to proper position by 80 manipulating the thumb wheel 52 and when the armature A is moved in one direction by means of the main spring S, while being unwound or expended to operate the clock mechanism, that on the contrary the main 85 spring will be rewound for a like amount when the armature A is forcibly turned throughout the same distance in the reverse direction by its attraction due to the action upon it by the magnetic field of the magnets 90 when produced by energizing the coils, as will be hereinafter more particularly described.

I will not describe the magnetically operated winding mechanism:

On the plate 24 is mounted two horseshoe magnets, the base of the magnets being illustrated at 100 and 102 and the exposed poles at 104, 106, 108 and 110. A winding of wire is provided around the poles at 112, 114, 116 100 and 118, and the ends of the wires from each pole are secured to a terminal screw 120, which is mounted by a nut 124 to the plate 26, the terminal being properly insulated by a spool of insulation 126 between the nut and the terminal plug 128. The line wire WS, leading from one pole of the battery B is suitably secured by a screw 130 to the end of the plug 128 which is suitably insulated from the casing 10 as by means of bushing 126A. 110 The other pole of the battery is connected by the wire WN at 132, to the metal casing 10. The wires from the other ends of the coils are permanently and electrically secured to the lower end of the terminal 133 which is 115 electrically connected to plate 134 and insulated from the frame.

The metal plate 134 is mounted upon a slab of insulating material 136, the said slab being secured to the plate 26, the plate 134 being provided with a turned over edge or flange 137 which lies closely to the inner edge of the plate of insulation 136.

As heretofore described, the armature is centrally mounted upon the sleeve 70, and it consists of a piece of soft iron so formed that four arms project in a radial direction from its center or hub. The ends of each of said arms extend over and are closely adjacent to the respective poles of the magnets so that 130

they will be positively and certainly affected by the fields of the magnets when the magnets are energized and will consequently be attracted to a position directly over the poles 5 of the magnets when the respective fields are created.

One of the arms of the armature which is positioned near to the plate 134, mounted upon the insulating slab 136, is provided 10 with an elongated slot 138, on one side of which near the outer end thereof is pivoted a contact lever 140 shown in detail in Fig. 10. This lever is provided with an anti-friction roller contact bearing 142 at one end 15 and with an upright flange 144 at the other end, the lever being pivoted at 146 to the armature arm, the inner free end of the lever being held by a spiral spring 148, one end of said spring being attached to the flange 144 20 and the other end to the hub of the armature at 150, thereby tending to cause the roller of the little contact lever to have a tendency to press outwards.

On the plate 26 is pivoted at 152 adjacent 25 the plate 134 a bell crank lever 154, commonly called a trap, illustrated in detail in Fig. 11, which bell crank lever or trap is provided at one free end with a bent up flange portion 157 and at the other free end with an aperture 30 158 to which is secured one end of a spring 160, the other end of said spring being secured to the base of an elongated opening 162 positioned as illustrated in Fig. 2 in the plate 26.

As will be readily understood, when the 35 sleeve 70 is turned on the shaft 50, by means of the operation of the main spring, the contact roller 142 will engage the inner surface 155 of the flange 157 of the trap, and when the contact lever is freed from the inner edge 40 159 of the flange 157, the spring 148 will cause the contact roller to engage with the inner flange 137 of the metal plate 134, thus closing the contact of the electric circuit, energizing the magnets, forming a field about 45 their poles, which immediately attracts the armature to cause it to turn in the opposite direction to wind the clock mechanism to the extent of the previous unwinding from that which it had been revolving. The arms of the 50 soft iron armature by this movement to the magnetic attraction will be positioned over the center of the poles of the magnets at which time the roller will be freed from contact with the flange of the metal plate 134 and brought 55 into engagement with the edge of the insulating plate, thus breaking the electric circuit from the battery to the magnets and enabling the main spring to again operate the clock for a time and move the armature arms from 60 over the poles of the magnet when the main spring again expends itself in the operation of the clock, the roller contact engaging itself with the inner surface 155 of the flange 157 of the trap, as shown in Fig. 3, which is always 65 spring held in a central position, by the

contraction of the spring 160. The roller contact is thus enabled in each cycle to pass by the respective ends of the flange 157 of the trap 154, so that the mechanism may repeat this operation again and again to the end 70 that as the main spring is unwound during its control of the movement of the clock, the expended portion is in turn again wound due to the oscillation of the armature when brought again to its position over the poles of the magnets because of the fact that the armature is 75 attracted to the poles of the magnet at and during each intermittent energization of the magnets.

As is shown particularly in Figs. 2, 3, 4 80 and 11, the trap 155 when rocked to catch the roller 142 on the inner face, forms a smooth uninterrupted continuation of the surface of the insulating block. Moreover, the smooth continuous surface thus formed has a curvature centered on the axis of the sleeve 70 and armature A, so that there is no appreciable resistance to the passage of the roller 142 throughout the entire path of movement of the armature. This has the advantage of 85 not interfering with the action of the main-spring and not introducing any irregularity or disturbing effects into the operation of the clock.

Having described the structure of the parts 90 of the mechanism embodying my invention and at the same time having referred to the functions resulting from the movements of those parts, I will now describe in general 95 the operation of the complete device.

The mechanical construction of the watch or clock is similar to an ordinary watch except that the main spring is mounted on a sleeve which rotates about and around the center supporting shaft. As above stated, certain 100 portions of the clock mechanism, such as the mainspring barrel and the connecting gears from the main clock winding gear 98 are not particularly referred to as necessary to a full 105 understanding of my invention.

Upon the same skeleton structure in which the clock mechanism is mounted is mounted the magnet equipment which consists of two horseshoe electro-magnets symmetrically and 110 equally spaced in a circle around the center shaft. The armature which is to be attracted by the fields of these magnets when energized has four arms which coincide exactly with the spacing of the magnets. The main spring of 115 the clock by its power drives the center unit of the shaft through the engagement of a gear wheel against a pawl mounted on a plate at the same time that the main spring operates the clock. Because of the fact that the armature is mounted on a sleeve, to which one end 120 of the main spring is secured, and is thus in fact an intrinsical part of the mainspring arbor, the mainspring power also causes the armature to rotate from the poles of the four electro-magnets. On the armature is a mov- 125 130

able spring actuated lever which is provided at one end thereof with a roller contact point, the lever being constantly under spring tension. During the backward movement of the 5 armature and lever caused by the operation of the main spring in the ordinary movement of the clock mechanism, the roller contact point on the lever, which latter is attached to the armature, is guided against a pivoted trap 10 so constructed and so placed that as it moves it increases the tension of the coil spring secured to the lever. When the roller contact point of the lever reaches the end of the trap, the spring forces the movable lever to strike 15 against the immovable contact plate, which is rigidly mounted upon an insulating slab, thereby closing the electric circuit of the battery and producing a field about the poles of the magnets. The armature is immediately 20 attracted by the fields of the four magnets and as this armature is mounted on the same sleeve as the mainspring arbor, the movement of this arbor winds up the mainspring. The actuation of the armature causes the contact 25 lever mounted upon it to move in the same direction and the roller contact continues to complete the electric circuit of the battery while it is engaged with the immovable contact plate. As soon as the roller leaves the 30 immovable contact plate and strikes against the piece of insulation upon which the immovable contact plate is mounted, the circuit is broken, and the fields of the magnets consequently cease to exist and the armature is no 35 longer attracted. In its movement, actuated by the magnetic attraction of the field of the armature, the roller contact momentarily dislodges a spring actuated pivoted trap, and the trap under spring tension will resume its nor- 40 mal position after the roller contact has cleared it. The trap will now act as a guide for the roller and during the subsequent movement of the spring roller along the guide flange of the trap a tension is placed on the 45 spring of the contact lever. During this movement of the armature, due to its attraction by the magnetic field, the sleeve mounted gear wheel moves slowly because of the fact that the spring pressed pawl passes idly over 50 the teeth on the periphery thereof, but when the magnet field ceases to exist the pawl engages the gear wheel and the main spring again operates the clock mechanism and carries the armature away from the poles of the 55 magnets. This operation, as above described, is repeated again and again, and it will last just as long as the battery is charged. Five or six minutes are consumed for the armature to travel back to the point at which the con- 60 tact is made, consequently, the main spring operates the clock mechanism every five or six minutes and in turn is rewound every five or six minutes, the tension of the main spring, therefore, remaining practically constant, all

of which will result in causing the clock to 65 keep more accurate time.

As will clearly appear from the above the design of the construction is extremely simple and the mechanism is very compact and the productive costs are very much lessened. 70

It is a practical impossibility to make an electric contact except at the proper time because of the fact that the contact is governed by the trap, and as the spring is in operation for a period of only five or six minutes at a 75 time and then rewound for repeated action, the force of the main spring is very constant, and the operation of the time piece is very regular.

Having thus described my invention what 80 I claim as new and desire to secure by Letters Patent is:

1. A device of the type described which comprises a clock mechanism, a driving shaft projecting from said mechanism, an electric 85 circuit, a pair of horseshoe electro-magnets in said circuit arranged symmetrically about said shaft with their yoke portions toward, and their poles projecting from, said clock 90 mechanism, an armature mounted on said shaft and having arms positioned to be drawn into the fields of said electro-magnets and to be drawn therefrom by said clock mechanism, a contact plate in said circuit, a lever mounted on said armature arm and having a contact 95 roller at one end to contact with said contact plate and close said circuit, a rocking trap plate movable to permit said roller to contact with said contact plate as said armature moves into the fields of said electro-magnets, and means to rock said trap plate to hold said contact plate upon the return movement of 100 said armature.

2. A device of the type described which comprises a clock mechanism, a driving shaft 105 projecting from said mechanism, a pair of horseshoe electromagnets arranged symmetrically about said shaft with their yoke portions toward, and their poles away, from said clock mechanism, an armature mounted on said shaft and movable into the field of said electro-magnet, a circuit for said electromagnets comprising a stationary contact plate and a pivoted lever on said armature having a contact and a spring acting on said lever for resiliently holding said contact against said contact plate, and a trap plate pivoted to lift and permit said contact to slide between it and said contact plate as said armature moves into said magnetic field and to interpose a lifting surface to separate said contact and contact plate as said armature is withdrawn from said magnetic field. 115

3. Apparatus of the type described which comprises a shaft, a pair of horseshoe electro-magnets symmetrically mounted in parallel relation about said shaft and having pole pieces, an armature mounted on said shaft 120

- and rotatable therewith in position to oscillate into and out of the magnetic field overlying said pole pieces, a main spring mounted on said shaft to drive a clock mechanism and 5 to urge said armature out of said magnetic field, an electric circuit including said electromagnets, a stationary insulated contact plate included in said electric circuit, a pivoted lever on said armature, means resiliently 10 pressing said lever against said contact plate and a trap plate pivoted adjacent said stationary contact plate to permit the contact end of said lever to pass between said stationary contact plate and said trap plate as said 15 armature moves into said electric fields, and means to tilt said trap plate when the armature reaches the end of its movement into said magnetic field to intercept the contact end of said lever and lift it from contact 20 with said contact plate until it reaches the opposite end of said trap plate, said horseshoe electromagnets being arranged with their yoke portions nearest to, and their poles pointing from, said mainspring.
- 25 4. A device of the type described which comprises a clock mechanism, a driving shaft projecting from said mechanism, a pair of horseshoe electromagnets arranged symmetrically about said shaft with their yoke 30 portions towards, and their poles away from, said clock mechanism, an armature mounted on said shaft having arms adapted to be attracted to and overlap the poles of said electromagnets and completing a magnetic circuit when said magnets are energized, and to be drawn therefrom by said clock mechanism when said electromagnets are de-energized, an electric circuit through said electromagnets, means for closing said electric circuit 35 when said magnets are energized, and to be drawn therefrom by said clock mechanism when said electromagnets are de-energized, an electric circuit through said electromagnets, means for closing said electric circuit when said armature arms are withdrawn to a limiting position by said clock mechanism and until said arms are drawn to overlap said pole pieces, and means for breaking said circuit when said armature arms overlap said 40 pole pieces and for holding said circuit open while said armature is drawn from said pole pieces.
5. A device of the type described which comprises a shaft, a clock driving means actuated by the rotation of said shaft in one direction, a pair of horseshoe electro-magnets distributed in spaced relation symmetrically about said shaft as a center, with their yoke 45 portions nearest said clock winding means and their poles away from said clock winding means, an armature on said shaft having arms movable into the fields of said magnets to rotate said shaft in a direction opposite to the driving means, an electric circuit 50 for energizing said electro-magnets, means for opening said circuit as said arms reach the end of their movement into said magnetic fields and holding said circuit open during the return movement and for closing said circuit at the end of the return movement,
- and holding it closed until said arms reach the end of their movement into said fields, said means comprising a yielding and resilient contact carried by said armature, a cooperating fixed contact, and an element for 70 deflecting said yielding contact out of contact with said plate member during a part of the movement of said armature in the clock driving direction.
6. A device of the type described which 75 comprises a shaft, a clock driving mechanism actuated by the rotation of said shaft in one direction, a pair of horseshoe electro-magnets distributed in spaced relation about said shaft as a center, with their yoke portions 80 nearest to, and their pole ends farthest from, said clock winding mechanism, an armature on said shaft having arms movable into the fields of said magnets to rotate said shaft in a direction opposite the driving movement, 85 a stationary contact plate, a contact carried by an armature arm and resiliently pressed against said contact plate, said contact plate and contact being included in the circuit of said electro-magnets, a tilting trap plate between which and said contact plate said contact passes as said armatures move into said magnetic fields, and means for swinging said trap plate between said contact and contact plate to separate them as said armature 90 reaches its end position in said field and during its return movement.
7. A device of the type described which 95 comprises a mainspring, an armature connected to said mainspring, an electric circuit, a pair of electro-magnets in said circuit to attract said armature upon the closing of said circuit, a contact plate in said circuit, an insulating plate having a surface adjoining that of said contact plate, a contact lever on 100 said armature resiliently pressed against said contact plate to close said circuit, said lever being drawn onto said insulating surface at the end of the movement of the said armature toward said electro-magnets, and a trap plate 105 to intercept said contact lever and separate it from said contact plate on the return of said armature from said electro-magnets by said mainspring, the intercepting face of said trap plate forming a smooth, uninterrupted 110 surface with said insulating surface and having a circular curvature concentric with the axis of said armature.
8. A device of the type described which 115 comprises a number of electro-magnets, a pivoted armature for said electro-magnets, means to withdraw said armature from the fields of said electro-magnets upon the de-energization of said electro-magnets, a circuit comprising said electro-magnets, a contact plate in said 120 circuit, a contact lever mounted on said armature and resiliently pressed against said contact plate to close said circuit when said armature is drawn out of the fields of said electro-magnets, an insulating plate having a 125
- 130

surface receiving the contact end of said lever at the end of its movement into the fields of said electro-magnets, and an insulated trap plate for intercepting and separating said contact end of said lever from said contact plate during the return movement of said armature from said electro-magnets, said trap plate having a surface of circular curvature concentric with the axis of said armature and continuous with said insulating surface.

9. A device of the type described which comprises a main-spring, an armature connected to said main-spring, an electric circuit, a pair of electro-magnets connected together at one end and having free pole pieces to attract said armature upon the closing of said circuit, a fixed contact in said circuit, a contact lever resiliently carried with said armature and contacting with said fixed contact when said lever is drawn by said main-spring to a maximum distance from said electro-magnets, means providing a smooth path for said contact lever during its return movement concentric with the axis of said armature and insulated from said fixed contact whereby said contact lever is moved by said mainspring without variation in resistance to movement during its travel towards said fixed contact.

10. A device of the type described which comprises a clock mechanism, a driving shaft for said mechanism, a horseshoe electro-magnet in longitudinal spaced arrangement to said shaft and having its yoke portion towards, and its pole pieces from, said clock mechanism, an armature mounted on said shaft with arms placed to be attracted to and overlap the poles of said electro-magnets when energized, and to be drawn thereby from said clock mechanism when said elec-

tro-magnets are de-energized, an electric circuit through said electro-magnets, means for closing said electric circuit when said arms are withdrawn to a limiting position by said clock mechanism and until said arms are drawn to said pole pieces, and means for breaking said circuit when said armature arms reach their limiting position towards said pole pieces and for holding said circuit open while said armature is drawn from said pole pieces.

11. A device of the type described which comprises a shaft, a clock winding means actuated by the rotation of said shaft in one direction, a pair of electro-magnets positioned longitudinally of, and in spaced relation to, said shaft, a yoke connecting the ends of said electro-magnets nearest said clock winding means to form said electro-magnets into a horseshoe magnet with the poles pointing from said clock winding means, an armature on said shaft having arms movable into the fields of said horseshoe magnet to rotate said shaft in a direction opposite that of its driving movement, an electric circuit for energizing said electro-magnets, means for opening said electric circuit as said arms reach the end of their movement into said magnetic fields, and holding said circuit open during the return movement, and for closing said circuit at the end of the return movement and holding it closed until said arms reach the end of their movement into said electro-magnetic fields, said means comprising a pivoted contact actuated by said armature, a co-operating fixed contact, and an element for holding said pivoted contact out of contact with said fixed contact during movement of said armature in the clock driving direction.

FREDERICK C. HERBERMANN.
